[57] CLAIM

The ornamental design for a flower pot cover, as shown and described.

DESCRIPTION

FIG. 1 is a perspective view of a flower pot cover showing my new design;

FIG. 2 is a top plan view thereof;

FIG. 3 is a bottom plan view thereof; and,

FIG. 4 is a side elevational view thereof, all sides being identical.

The horizontal cross-hatch pattern and the diagonal cross-hatch pattern represents contrasting surface effects on the inside of the inner layer and the outside of the outer layer of the flower pot cover shown in FIGS. 1-4; each contrasting surface effect is understood to repeat uniformly across the circumscribed surfaces. The flower pot cover has no substantial thickness.
